CLAIM

We claim the ornamental design for a decorative-flame burner, as shown and described.

DESCRIPTION

FIG. 1 is a perspective view of a decorative-flame burner.

FIG. 2 is a front view of the decorative-flame burner.

FIG. 3 is a rear view of the decorative-flame burner.

FIG. 4 is a left-side view of the decorative-flame burner.

FIG. 5 is a right-side view of the decorative-flame burner.

FIG. 6 is a top view of the decorative-flame burner; and,

FIG. 7 is a bottom view of the decorative-flame burner. The broken lines in the Figures are directed to unclaimed subject matter of the decorative-flame burner, and the broken lines form no part of the claimed design.
